COATING APPARATUS.

Application filed October 30, 1925. Serial No. 65,743.

This invention relates to improvements in apparatus for applying inflammable liquid coating compositions, such as cellulose ester lacquers containing cellulose nitrate or inflammable solvent or diluent materials.

Cellulose ester lacquers usually comprise a solution of cellulose nitrate in solvent or mixture of solvents such as ethyl acetate or butyl acetate or a mixture of such solvents, together with diluents such as turpentine, toluol or petroleum benzine. Such solvents or diluents frequently undergo rapid evaporation, even at ordinary temperature, and, as their vapors, when in admixture with air, readily take fire, a hazard of fire or explosion is involved. For certain purposes it has been found advantageous to apply such lacquers by dipping operations, but for the treatment either of a large number of small objects or of objects having considerable surface area the volume of the dipping bath required is so great that the fire or explosion hazard is considerably increased; for example, as compared to an operation in which the lacquer is applied by spraying.

It is one of the objects of this invention to provide an apparatus for applying such lacquers, or other inflammable liquid coating compositions, in which the danger of fire or explosion is materially reduced if not substantially eliminated, and which reduces to a minimum damage due to any fire or explosion that may occur. Other objects and advantages of the invention will appear as the description proceeds.

The apparatus of the present invention is of special value and application for carrying out the process described in my application filed August 19, 1925, Serial No. 51,201.

In the apparatus of the present invention, the liquid coating composition is applied by dipping. The dipping is effected in a dipping bath comprising a layer of the coating composition floating on a non-inflammable liquid body, the floating layer of coating composition forming a film over the object or objects being dipped as they pass through the floating layer into the supporting body of non-inflammable liquid permitting the object or objects to be coated to any desired extent. The volume of the liquid coating composition necessary to employ is thus materially reduced, it may even

be but a small fractional part of that volume required for complete immersion of the object or objects to be coated, so that the amount of inflammable material and consequently the risk involved is likewise reduced. Further to reduce the hazard, according to the present invention, means are provided for withdrawing the relatively small volume of liquid coating composition employed from the dipping operation with any dangerous rise in temperature. Where the use of a very large volume of an inflammable coating composition is involved, it is extremely difficult if not impossible to remove the coating composition sufficiently quickly to prevent a serious conflagration if a fire starts; but, by providing an apparatus in which a relatively small amount of the coating composition is employed at any one time, the withdrawal of this relatively small amount can be effected with sufficient rapidity, in accordance with this invention, to prevent fire or to avoid any serious conflagration in case of a fire.

The invention will be further described in connection with the accompanying drawings, which illustrate in a diagrammatic and conventional manner apparatus embodying the invention, but it will be understood that this further and more detailed description and illustration are for the purpose of exemplification only, and that the invention is not limited thereto. In the accompanying drawings,

Fig. 1 represents in elevation and partly in section with parts broken away one form of apparatus embodying the invention,

Fig. 2 is a fragmentary end view with parts broken away of the dipping tank illustrated in Fig. 1,

Fig. 3 represents in elevation with parts broken away a modified form of apparatus embodying the invention, and

Fig. 4 represents a further modification of apparatus of the general type illustrated in Fig. 3.

Referring particularly to Figs. 1 and 2, a dipping tank 5 adapted to contain a non-inflammable liquid body 6 is arranged beneath a vertical movable frame or track 7. The objects to be dipped are supported from a truck or carriage 8 which during the dipping operation is carried on the frame 7. The carriage 8 is movable on to and off of the frame 7, and by providing a number of

these carriages successive dipping operations can be carried out rapidly by running the carriage supporting the object or objects which have just been dipped off of the frame 7 and replacing it with a carriage supporting the object or objects next to be dipped. To provide for regular and controlled vertical movement of the frame or track 7, one end of the frame is supported by a plunger 9 of 10 a hydraulic jack 10 and the other end of the frame or track is supported by a wire rope or equalizing cable 11 running over suitable pulleys and connected to the end of the frame or track adjacent the plunger so that 15 vertical movement of the frame or track will be uniform at both ends. To operate the hydraulic jack, fluid under pressure from connection 12 is supplied to the two-way valve 13 which also communicates with 20 the chamber of the jack through connection 14 and an outlet connection 15. The valve 13 is arranged to permit the introduction of fluid under pressure from connection 12 into the jack chamber or to permit the escape of 25 fluid from the jack chamber through connection 14 or to close the jack chamber. The valves 16 and 17 are provided in the fluid inlet and fluid outlet connections, respectively, for regulating the rate of flow of 30 fluid therethrough and thereby the rate of vertical movement of the track or frame 6. An exhaust fan 18 is arranged for the removal of vapors arising from the dipping tank 5. A pair of hinged covers 19 and 20 35 are also provided to close the upper end of the dipping tank when not in use to assist in reducing evaporation losses.

The liquid coating composition to be applied to objects dipped in the tank is floated 40 on the liquid body 6 so that a layer of the coating composition is provided over the upper surface of the liquid comprising the major part of the contents of the dipping tank. The supporting liquid body is of a 45 non-inflammable nature; for example, with cellulose ester lacquers, the non-inflammable liquid body may be water or an aqueous saline solution, as described in my application above identified. The liquid coating composition may, for example, be supplied to the dipping tank through supply 50 connection 21. An outlet 22 is provided communicating with the interior of the dipping tank at a point adjacent the normal liquid 55 level of the non-inflammable body on which the coating composition is supported. A valve 23 is provided in the connection 24 from the outlet 22 which is normally closed but which is capable of operation to open 60 the connection permitting discharge through the outlet 22 and the connection 24. Manual or automatic means or both may be provided for operation of this valve.

In the apparatus illustrated, automatic 65 temperature responsive means effective to

open the valve at a predetermined temperature, for example a temperature less than that resulting if the coating composition in the tank takes fire, are provided. This temperature responsive means comprises a fusible link 25 connected to a chain or cable 26 supporting an arm 27 on the stem of the valve 23 against the pull of the weight 28 so that a temperature sufficient to melt the link 25 causes the opening of the valve 23 by releasing the weight 28. It will be apparent that in normal operation the provision of the outlet connection 22 has no effect, but in case of a dangerous rise in temperature this outlet connection provides for withdrawal of the entire volume of inflammable coating composition floating on the non-inflammable liquid body in the dipping tank, the outlet being arranged adjacent the normal liquid level of the non-inflammable supporting liquid body.

To promote rapid withdrawal of the inflammable liquid coating composition from the dipping tank, several expedients may be employed, for example, a tank continuously maintained under sub-atmospheric pressure may be connected to the outlet connection so that upon opening of the valve in the outlet connection the liquid material in the dipping tank above the outlet connection is immediately withdrawn, or a tank may be arranged at a level below the dipping tank so that the liquid in the dipping tank above the outlet will flow into it by gravity, or a pump discharging at a point away from the dipping tank may be connected to the outlet and arranged to be set in operation at the same time that the valve in the outlet connection is opened.

In the apparatus illustrated in Figs. 1 and 2, a safety tank 31 is connected to the outlet 22 through connections 29 and 24, and a vacuum pump 30 is arranged in communication with the tank 31 so that a pressure well below atmospheric pressure may be maintained therein throughout the period of operation. With this arrangement, immediately upon opening of the valve 23 so much of the contents of the dipping tank as are inflammable are immediately forced into the closed tank 31 by the excess of atmospheric pressure. This form of apparatus is particularly advantageous where a very large dipping tank is employed, as with this arrangement the dipping tank may then be located on the ground level and the safety tank may be provided without requiring any excessive excavation.

In the form of apparatus illustrated in Fig. 3, a tank 32 is arranged at a level sufficiently below the level of the outlet connection 22 so that the natural head provided will effect the rapid discharge of the inflammable contents of the dipping tank. The tank 32 is a closed tank and is vented through

connection 33 to a point sufficiently remote to eliminate fire hazard so that the safety discharge system cannot become air bound. The connection 34 between the valve 23 and the tank 32 is extended into the tank to a point just above the bottom thereof to provide a seal preventing the escape of gases and vapors from the dipping tank into the tank 32 to eliminate any possibility of ignition of the contents of tank 32 by transmission of fire through the connections between this tank and the dipping tank. This form of apparatus is advantageous where it is convenient to arrange the safety tank at a substantial distance below the dipping tank.

As the volume of liquid coating composition in the dipping tank of the present invention is always relatively small, the supply of liquid coating composition in the dipping tank is rapidly depleted in operation, and it is accordingly convenient to provide for automatic maintenance of the supply of liquid coating composition in the dipping tank during normal operation. An apparatus for accomplishing this is illustrated in Fig. 4. A supply tank 35 is arranged at a level somewhat above the liquid level in the dipping tank. This supply tank is normally closed but is provided with a removable cover 36 to permit the replenishing of the supply of liquid coating composition therein. When the cover 36 is to be removed, valves 37 and 38 are closed, and are kept closed until the cover 36 is again tightly in place. One connection 39 is provided from the lower part of the supply tank to a point somewhat below the normal upper level of the layer of liquid coating composition in the dipping tank, and another connection 40 extending into the supply tank to a point closely adjacent the upper end thereof is provided communicating with the interior of the dipping tank at the normal upper level of the layer of liquid coating composition. As the liquid coating composition is consumed, the level in the dipping tank falls below the opening into connection 40 permitting the escape or air therethrough into the supply tank and consequently permitting the flow of liquid coating composition from the supply tank through the connection 39 into the dipping tank until the opening of connection 40 is again covered.

As this arrangement would permit of the dumping of the entire contents of the supply tank into the dipping tank in case of opening of the safety discharge outlet, means are provided for closing the connections 39 and 40 between the supply tank and the dipping tank whenever the valve 23 in the discharge connections communicating with the safety outlet 22 is opened. In the apparatus illustrated in Fig. 4, these means comprise a pair of valves 41 and 42 connected to the cable 26 between the fusible link and the weight

supporting arm 27 on the valve 23. The release of the weight 28 thus operates to close the valves 41 and 42, and consequently to close communication between the supply tank and the dipping tank simultaneously with the opening of valve 23.

It will thus be seen that the present invention provides an improved apparatus for applying inflammable coating compositions by dipping in which the fire hazard is at a minimum. By providing a non-inflammable liquid body in the dipping tank on which but a relatively small amount of the inflammable liquid coating composition is supported, the risk is reduced because of the smaller quantity of inflammable material exposed in the dipping tank. By further providing for quick withdrawal of the inflammable material present, the danger is further reduced. The provision of dipping means employing but a relatively small amount of the inflammable coating composition reduces the risk not only because of the smaller volume of material present but in the apparatus of the invention also because it enables more rapid withdrawal of the inflammable material.

I claim:

1. An apparatus for applying inflammable liquid coating compositions, comprising a dipping tank having a non-inflammable liquid body therein upon which floats a layer of the coating composition, an outlet communicating with the interior of the tank at a point adjacent the top surface of the said non-inflammable liquid body, and temperature responsive means effective at a predetermined temperature to cause the withdrawal through the said outlet of coating composition floating on the said non-inflammable liquid body in the tank, without substantial removal of the non-inflammable liquid body.

2. An apparatus for applying inflammable liquid coating compositions, comprising a dipping tank having a non-inflammable liquid body therein upon which floats a layer of the coating composition, an outlet communicating with the interior of the tank at a point adjacent the top surface of the said non-inflammable liquid body whereby to prevent substantial removal of the non-inflammable liquid body, means for withdrawing coating composition floating on the said non-inflammable liquid body connected to the said outlet, and means interposed in the connection between the outlet and the last named means normally closed but capable of opening the said connection.

3. An apparatus for applying inflammable liquid coating compositions, comprising a dipping tank having a non-inflammable liquid body therein upon which floats a layer of the coating composition, an outlet communicating with the interior of the tank at a point adjacent the top surface of the

said non-inflammable liquid body whereby to prevent substantial removal of the non-inflammable liquid body, temperature responsive means effective at a predetermined 5 temperature to cause the withdrawal through the said outlet of coating composition floating on the said non-inflammable liquid body in the tank, and means for preventing the escape of gases and vapors from the tank 10 through the said outlet.

4. An apparatus for applying inflammable liquid coating compositions, comprising a dipping tank having a non-inflammable liquid body therein adapted to float a layer 15 of the coating composition, an outlet com-

municating with the interior of the tank at a point adjacent the normal liquid level of the said non-inflammable liquid body, supply means connected to the tank adapted to maintain a layer of the coating composition to a 20 predetermined level in the tank, and temperature responsive means effective at a predetermined temperature to close the connections between the tank and the said supply means and to cause the withdrawal through 25 the said outlet of coating composition floating on the said non-inflammable liquid body in the tank.

In testimony whereof I affix my signature.

REME A. BEAUSEJOUR.
